Melvin H. Boldt, Glenview, Ill., assignor to Zenith Radio Corporation, a corporation of Delaware

Application December 24, 1958, Serial No. 53,896

Term of patent 14 years

(Cl. D56—4)

FIG. 1

FIG. 6

FIG. 4

FIG. 3

FIG. 5

FIG. 2

Figure 1 is a perspective view of my design for a combined clock and radio;

Figure 2 is a top plan view thereof;

Figure 3 is an elevational view of a first side thereof;

Figure 4 is an elevational view of a second side thereof;

Figure 5 is an elevational view of a third side thereof; and

Figure 6 is a bottom plan view thereof.

The triangular housing of my design is pivotally connected to the legs and can therefore assume any angular position in relation thereto.

The dominant features of my design reside in those portions of the drawing shown by means of full lines.

I claim:

The ornamental design for a combined clock and radio, substantially as shown and described.
